[57] CLAIM

The ornamental design for a vehicle tire, as shown and
described.

DESCRIPTION

FIG. 1 is a perspective view of a vehicle tire showing
our new design, it being understood that the tread pattern
is repeated throughout the circumference of the
tire as shown schematically by solid lines and the oppo-
site side is the same as that shown; and,
FIG. 2 is a fragmentary, enlarged plan view thereof.

FIG. 1.

FIG. 2.
